Attorney

UNITED STATES PATENT OFFICE

HARRY DAUM, OF PITTSBURGH, PENNSYLVANIA

FURNACE CONSTRUCTION

Application filed July 10, 1928. Serial No. 291,560.

This invention, which relates to an improvement in the construction of melting furnaces and more particularly to an improvement in the construction of open hearth furnaces, has for its object to provide a new type of bulkhead in furnaces of the character referred to, especially adapted to greatly increase the life of such bulkheads and to eliminate the large repair costs occasioned by the 10 type of bulkheads now in use.

Another object of my invention is to provide a bulkhead construction which will entirely dispense with the laborious task of making hot repairs, as is now done with the 15 ordinary type of bulkhead.

A further object of my invention is to provide a bulkhead construction of such character that the products of combustion will be conducted from the furnace in such a manner 20 as to so temper the bricks in the bulkhead that it will be almost impossible to burn them away.

In setting forth the improved details of construction of my bulkhead, the purpose of 25 my invention will be best understood by referring to the conditions which exist everywhere with the bulkheads as they are built at present.

In the operation of any open hearth furnace, the products of combustion after passing across the hearth, are conducted across 30 a bridge wall into downtakes or ports, then to the regenerative chambers and thence to the stack.

As there are ports at either end of the hearth, it is customary at stated intervals to 35 reverse the path of travel of the products of combustion to the stack; that is to say that for a period of from fifteen to twenty minutes the products of combustion will be conducted to the stack through the ports of one end of the furnace, and then for an equal period of time they will be conducted 40 through the ports in the opposite end of the furnace.

That part of the furnace wall which forms the end of the furnace and which also is the outer end wall of the port or downtake is known as the bulkhead. The bulkhead is 45 built of a highly refractory material, usually

silica brick. The products of combustion as they pass over first the melting charge and later the liquid slag, pick up and carry with them finely divided particles of iron oxide, lime, and other chemical compounds. 55

The three major causes of the short life of bulkheads are: (1) the extreme high temperature of the outgoing products of combustion, (2) their velocity, and (3) the slagging of the bricks caused by their reacting 60 with the chemical compounds carried over by the combustion products.

The combined action of these three conditions cause most bulkheads to wear through 65 on from fifty to seventy-five heats, whereas the remainder of the furnace is good for from three hundred to six hundred heats, depending on the type of furnace and the grade of steel being made. 70

One method being used to hold the bulkheads in place is the installation of costly water-cooled equipment. This requires a heavy outlay of money, and means that thousands of gallons of water must be used every day, and when a leak occurs, the efficiency of 75 the furnace is greatly decreased.

But even with the water-cooled equipment the bulkheads burn away and when the bricks are only two or three inches thick, the chilling effect of the cooling water is so great that 80 the entering gases become chilled and the fuel consumption of the furnace is greatly increased. Finally, the gases become so much affected by the water that the furnace must be shut down to rebuild the bulkhead. My 85 invention makes it possible to eliminate all this expensive equipment and to dispense with all water about the bulkhead.

These and other objects I attain by the construction shown in the accompanying 90 drawing, wherein for the purpose of illustration is shown a preferred embodiment of my invention and wherein:

Figure 1 is a section on the line 1—1 of 95 Figure 2;

Figure 2 is a vertical longitudinal section of the port end of an open hearth furnace;

Figure 3 is a section on the line 3—3 of Figure 1.

Referring now more particularly to the 100

drawing, the numeral 10 indicates the usual or ordinary bulkhead of an open hearth furnace. I place in advance of this bulkhead another wall or bulkhead 11 which parallels the bulkhead 10 in spaced relation thereto, so that between the bulkheads, a passage 12 is formed. Extending through this passage are preferably disposed tie elements 13 which may conveniently be formed by bricks, the ends of which form a portion of each of the walls. The passage 12 at its lower end communicates with downtakes 14 of the hearth which are preferably located in advance of the wall 11.

In the operation of a furnace with a bulkhead of this character, the outgoing products of combustion come into contact with the wall 11 and a portion thereof deflected downwardly to pass through the downtakes 14. The remainder of the combustion products pass through the openings 15 formed in the wall 11 to the space 12 and pass downwardly in this space to the downtakes, where they join that portion of the gases which has been deflected by the wall 11. This wall 11 is thoroughly honeycombed with the openings 15, so that a goodly portion of the products of combustion will pass to the downtakes through the passage 12. It will at once be obvious that by splitting the gases in the manner just described their action upon the bulkhead 10 is materially relieved, but at the same time the bulkhead 10 is being thoroughly tempered. Now when the wall 11 has been destroyed, the bulkhead 10 has become so well glazed that it is practically immune to any further action of the combustion products, so that a bulkhead that will endure throughout the furnace campaign is attained.

The temperatures in the vicinity of the bulkheads are usually from perhaps 2700° F. to about 3000° F., so that bricks containing silica, chrome, magnesite, etc., will become vitrified or glazed by the heat of the bypassed gases, and before the temporary or baffle wall has become worn away by the main stream of hot gases. While the temporary wall 11 may contain silica or other vitrifying material, it is worn away so rapidly that ordinarily no protecting glaze is formed thereon.

Since the construction hereinbefore set forth is capable of a certain range of change and modification without materially departing from the spirit of the invention, I do not limit myself to such specific structure except as hereinafter claimed.

I claim:—

1. The step in the making of furnaces, which comprises installing a wall containing vitrifiable material, and placing a temporary wall in position to deflect a portion only of the gases from contact with the first-named wall, the temporary wall being of such char-

acter that it will not be destroyed by the said gases until after a glaze has formed on the first-named wall.

2. In a regenerative furnace, downtakes, a main bulkhead wall adjacent the downtakes and a relatively short-lived false bulkhead arranged inwardly of the bulkhead wall and spaced therefrom to provide therebetween a downwardly-extending passage the lower end of which is in communication with the downtakes, the false bulkhead having openings permitting the passage of gases to said space and the main bulkhead wall containing vitrifiable material.

3. In a regenerative furnace and in combination with the bulkhead thereof, a relatively short-lived baffle arranged in advance of the bulkhead and directing a portion of the gases downwardly before they come into contact with said bulkhead and downtakes conducting gases deflected downwardly by said baffle and by the bulkhead from the furnace, the said bulkhead containing vitrifiable material.

4. In a regenerative furnace, a bulkhead containing vitrifiable material, a relatively short-lived perforated wall opposing the bulkhead in spaced relation thereto and tied to the bulkhead and downtakes communicating with the space between the bulkhead and wall and adapted to receive gases deflected by said wall.

5. In a regenerative furnace, downtakes, a bulkhead wall adjacent the downtakes and containing vitrifiable material, and a relatively short-lived false bulkhead arranged inwardly of the bulkhead wall and spaced therefrom to provide therebetween a downwardly-extending passage the lower end of which is in communication with the downtakes, the false bulkhead having openings permitting the passage of gases to said space, and means connecting the bulkhead and false bulkhead and forming a portion of each thereof.

6. In a regenerative furnace and in combination, downtakes, a bulkhead containing vitrifiable material for directing gases to said downtakes, and temporary means in advance of the bulkhead deflecting a portion of the gases to said downtakes and preventing direct contact of said portion of gases with the bulkhead wall.

In testimony whereof I hereunto affix my signature.

HARRY DAUM.
